UNITED STATES PATENT OFFICE.

HANS M. OPSETH, OF MADISON, MINNESOTA.

BROODER.

1,139,459.

Specification of Letters Patent. Patented May 11, 1915.

Application filed July 18, 1914. Serial No. 851,791.

To all whom it may concern:

Be it known that I, HANS M. OPSETH, a citizen of the United States, residing at Madison, in the county of Lac qui Parle and State of Minnesota, have invented certain new and useful Improvements in Brooders, of which the following is a specification, reference being had to the accompanying drawings.

10 This invention relates to certain improvements in brooders and the object of the invention is to provide a novel and improved device of this general character which may be readily and conveniently assembled into 15 operative position and whereby an even temperature may be maintained.

The invention consists in the details of construction and in the combination and arrangement of the several parts of my improved brooder whereby certain important advantages are attained and the device is rendered simple, less expensive and otherwise more convenient and advantageous for use, all as will be hereinafter more fully 25 set forth.

The novel features of the invention will be carefully defined in the appended claims.

In order that my invention may be the better understood, I will now proceed to describe the same with reference to the accompanying drawings, wherein is disclosed a longitudinal vertical sectional view taken through a brooder constructed in accordance with an embodiment of my invention.

35 As disclosed in the accompanying drawings, A denotes a base section comprising a floor 1 of predetermined configuration and dimensions provided at its margins with the upwardly directed flange 2, on which is adapted to be rested the removable floor 3 having produced at substantially its center a circular opening 4 and having its upper surface provided with a covering 5 of felt, paper or the like.

45 The outer faces of the marginal flanges 2 are provided with a longitudinally disposed shoulders 6 which may be produced as desired and on which are adapted to rest the lower edges of the top section B of a predetermined height and having the central longitudinal portion of its top flat, as indicated at 6, and with the opposite longitudinal marginal portions disposed on a downward incline, as indicated at 7, said portions 7 being loosely disposed beneath the flat por-

tion 6 so that they may be readily removed in order to afford a convenient means of access within the brooder. In the opposite side walls 8 of the top section B, I find it of advantage to provide the suitably protected windows 9, while in one of the ends 10 I provide a door 11, for a purpose which is believed to be self-evident. I also find it of advantage to line the inner surfaces of the side and end walls and top of the 65 brooder with felt, paper or the like.

Projecting upwardly from the floor 3 and substantially surrounding the opening 4 therein is the cylindrical barrel or sleeve 12 having its upper extremity open and adapt-

ed to be intersected by the removable reticulated cloth 14 in order to prevent occupants of the brooder from falling within said barrel. While the barrel 12 may be maintained in operative position in any manner which

may be employed with facility, I particularly desire to apply the same as disclosed in the accompanying drawings, wherein the lower extremity of said barrel is disposed through the opening 4 and has its lower end

portion provided with a laterally disposed annular flange 15 which is adapted to be suitably anchored to the adjacent or under face of the floor 3. The barrel 12 is of such a height as to entirely inclose the upper portion of the heating medium 16 which

may be in the nature of an ordinary hydrocarbon lamp, which is adapted to rest upon the base 1 of the lower section A, and in order that such heating medium or lamp

16 may be applied into operative position with convenience and facility, I provide the portion 6 of the top of the upper section B with an opening 17 of a size similar to and adapted to aline with the opening 4 produced in the floor 3.

In order to retain the heat within the brooder, I dispose over the opening 17, the inverted cap member 18 having produced in the walls thereof the openings 19 where by proper ventilation within the brooder is assured, and in order to properly position such cap member 18, I find it of advantage to produce upon the portion 6 of the top member B, the annular bead 20 arranged around and concentric to the opening 17 with which the wall of the cap member 18 contacts, as is believed to be clearly shown in the accompanying drawings.

In order to prevent the chicks from con-

tacting with the barrel 12 or from passing directly over the open end of such barrel, I surround the barrel by the reticulated cylinder 21 secured at its lower extremity to the floor 3 and at its opposite extremity to the top of the section E, as is believed to be clearly shown in the accompanying drawings. I also find it of advantage to cover the top of the section B with the covering 10 22 of fabric roofing or the like in order to prevent ingress of moisture.

From the foregoing description, it is thought to be obvious that a brooder constructed in accordance with my invention 15 is of an extremely simple and comparatively inexpensive nature and is particularly well adapted for use by reason of the convenience and facility with which it may be assembled, and it will also be obvious that my invention 20 is susceptible of some change and modification without material departure from the principles and spirit thereof and for this reason I do not wish to be understood as limiting myself to the precise arrangement 25 and formation of the several parts herein shown in carrying out my invention in practice.

I claim:

1. A device of the character described 30 comprising a base section provided with upstanding marginal flanges, a floor rested upon said flanges, a top section disposed above the bottom section and overlying the flanges of the bottom section, said top section and floor being provided with alined 35 openings, an upstanding barrel surrounding the opening of the floor, a heating medium adapted to be supported by the base section and insertible through the openings in the 40 top section and the floor, and a cap member

adapted to be positioned above the opening in the top section.

2. A device of the character described 45 comprising a base section provided with upstanding marginal flanges, a floor rested upon said flanges, a top section disposed above the bottom section and overlying the flanges of the bottom section, said top section and floor being provided with alined 50 openings, an upstanding barrel surrounding the opening of the floor, a heating medium adapted to be supported by the base section and insertible through the openings in the top section and the floor, and a cap member 55 adapted to be positioned above the opening in the top section, said top section being provided with a bead to maintain the cap member in operative position.

3. A device of the character described 60 comprising a base section provided with upstanding marginal flanges, a floor rested upon said flanges, a top section disposed above the bottom section and overlying the flanges of the bottom section, said top section and floor being provided with alined 65 openings, an upstanding barrel surrounding the opening of the floor, a heating medium adapted to be supported by the base section and insertible through the openings in the top section and the floor, a cap member 70 adapted to be positioned above the opening in the top section, and a reticulated body removably disposed across the upper end of the barrel.

In testimony whereof I hereunto affix my 75 signature in the presence of two witnesses.

HANS M. OPSETH.
